DOOR CHIME AND WICKET MECHANISM

Murry Tall, New Rochelle, N. Y.

Application September 8, 1952, Serial No. 308,430

17 Claims. (Cl. 116—141)

The present invention relates to an improved door chime and wicket apparatus for installation directly on the door of an apartment or other dwelling.

It is the general object of the present invention to provide an improved door chime structure which is capable of being operated by a push or a pull, as by means of a button which can be depressed, or by a knocker or the like which can be swung away from the door to exert a pull on the chime-operating mechanism.

A particular object of the invention is to provide a chime mechanism which can be operated either by a push or pull and without in any way changing the operating mechanism, other than the replacement of the finger-engaged push element by the pull element, or vice versa.

A further and important object of the invention is to provide a mechanically operated chime mechanism wherein damping of the chime bars by the striker following impact is prevented by a spring acting on the striker.

More specifically, it is an object of the present invention to provide a manually operated push-pull door chime which is characterized by simplicity of construction, compactness, and reliability in operation.

Still more specific objects of the invention are to provide in a chime structure, an improved mounting for the striker; to provide a chime structure operable from a manually movable member which can be pushed in one direction or pulled in the opposite direction, and in which both chime bars are sounded during the pushing or pulling of the manually operated member and its return movement; to provide a chime structure so constructed as to produce a minimum of noise from the movement of its operating parts; and to provide a chime bar operating mechanism of so few metallic parts that they can all be struck from the metallic base plate of the chime structure.

The present invention contemplates further the combination of a door chime, particularly one of the type above indicated, with a door wicket or peep hole wherein the chime structure and wicket structure have certain parts in common, whereby a simplified and cheaper combined structure is obtained.

Other objects and advantages of the invention will appear from the following detailed description thereof.

The invention will be further described in connection with the attached drawings illustrating several satisfactory embodiments of the invention by way of example. In said drawings,

Fig. 1 is a rear elevational view of the chime mechanism, showing movable parts in normal positions, the cover being removed; Fig. 2 is a side elevational view of the chime bar operating mechanism with the chime bar broken away for the most part to avoid obscuring the strike, together with the manual actuating means therefor; Fig. 3 is a front elevational view of the shield, mirror and knocker; Fig. 4 is a fragmentary side elevational view of a door showing partly the chime mechanism housing,

which incorporates one form of wicket, mounted on the inner surface of the door, and the shield and knocker mounted on the outer face of the door; Fig. 5 is a rear elevation of the upper portion of the interior of the chime mechanism housing, showing the wicket and its operation; Fig. 6 shows a fragmentary rear elevational view of the chime mechanism, with the movable parts in the positions assumed when the first of two chime bars is struck by the striker in response to a pushing movement of the operating link, as from the outside of the door by means of a push-button; Fig. 7 is a fragmentary side elevational view of the chime mechanism, corresponding to Fig. 6, with one chime bar broken away to show certain moving parts; Fig. 8 is a fragmentary rear elevational view of the chime mechanism showing movable parts in positions assumed when the first of two chime bars is struck by the striker in response to a pulling movement of the link, as from the outside of the door, by means of a knocker, a pull-knob, or the like; Fig. 9 is a fragmentary side elevational view of the chime mechanism, corresponding to Fig. 8, with one chime bar broken away to show certain moving parts; Fig. 10 is an elevational view of another type of wicket structure suitable for employment with the present chime mechanism, the view being taken from the inside of the door; Fig. 11 is an obverse elevational view of this same wicket structure; Fig. 12 is a section along the line 12—12 of Fig. 11; Fig. 13 is a largely diagrammatic side elevational view of the complete structure, embodying the wicket of Figs. 10 to 12; Fig. 14 is a rectilinear perspective view of a yoke adapted to actuate the chime mechanism striker in response either to a pushing or pulling movement of a link passed through an aperture of the door; Fig. 15 shows a preferred structure for preventing damping of the chime bars; Figs. 16 and 17 show a top plan and an end view, respectively, of mechanism for controlling the tone of the chime bars, while at the same time eliminating stop devices for limiting the throw of the striker; Figs. 18 and 19 show, respectively, an external and inside view of a gravity-controlled shutter for the wicket; while Fig. 20 is a section along the line 20—20 of Fig. 19.

The drawing illustrates different forms of combined chime and wicket structure adapted to be mounted on the door of a dwelling or the like. The signalling element to be operated by a caller at the outside of the door may be a knocker, as shown in Figs. 2 and 3, a push button, as shown in Fig. 7, or any other suitable pull or push device. In accordance with one of the features of the invention, the chime mechanism may be operated either by a push or a pull and without alteration of the operating member or of their relationship. Common to the illustrated forms of the invention are the exterior peephole shield or face plate, and dark mirror, the link passed through the door, and the chime mechanism.

In the drawing, wherever shown, the door is designated 10, the peephole window 11, the aperture for the link, 11a, and the link itself, 12. The shield is designated 13, the dark mirror 14, and the entire chime mechanism 15.

A preferred manner of preparing a door for the installation of the apparatus of the invention is that of boring or fly-cutting a relatively large window for the peephole and boring or otherwise providing a relatively small aperture beneath the peephole to accommodate the link. See particularly Fig. 2.

A typical appearance of the installed invention, as seen from the outer side of the door, is best illustrated in Fig. 3, which is a front elevational view of the shield 13, having, in this instance, a stirrup-type knocker 16.

The manner in which the apparatus, in either form, is mounted on a door is best seen in Fig. 2, wherein the door 10, the shield 13, the dark mirror 14, and the

knocker 16 are shown in section according to the plane 2-2 of Fig. 3. A side elevation of the chime mechanism is incorporated in Fig. 2, the nearer of two chime bars 17 and 18 being broken away to expose certain parts. Here the housing 19 of the mechanism is shown partly broken away and partly in section. This form of housing, the upper part of which is shown, together with part of the door, and the shield and knocker, in Fig. 4, is provided with a wicket having a peephole 20 seen in Fig. 5 which shows the interior of the upper part of the housing 19. The wicket aperture 20 is normally covered by a gate or shutter 21 pivotally mounted on the inside of the housing at 22. Slidably mounted in the upper part of housing 19 is a push bar 23, which is spring loaded, as at 24, to maintain it normally in the solid line position of Fig. 5. A pin 25 extending from the shutter 21 is freely received in an aperture 26 provided in bar 23. When the end 27 of bar 23 is pressed in the direction shown by the arrow in Fig. 5, the shutter 21 is rotated from the position shown in solid lines to that shown in dot-and-dash lines, and accordingly uncovers the wicket opening. Upon release of the bar 23, the spring 24 returns the shutter to closed position.

As can best be seen from Fig. 2, the knocker 16 associated with the wicket is connected by link 12 which passes through aperture 11a, with the chime mechanism 15.

The shield is preferably a die casting, and is provided, as shown in Figs. 2 and 3, with a central square window 28 which is covered on the inner side of the shield with the dark mirror 14 (Fig. 2). Above window 28 is a slot 29 for an apartment number card 30, the card being visible from the front of the shield through a smaller window 31. Beneath window 28 is a slot 32 for a name card, not shown, but which, when in place, may be seen through another window 33.

The stirrup type knocker 16, shown in Figs. 2, 3, and 4 is pivotally mounted on the shield by means of ears 34 which are received freely within sockets 35 provided at the sides of the shield. Provided on the rear of the handle 36 of the knocker is a lug 37 having an aperture 38 extending from top to bottom thereof. The link 12 is provided at its forward end with a fork 39. The tines of this fork may be bent downwardly and upwardly in aperture 38 to connect the link 12 to knocker 16.

The chime mechanism is shown in rear elevation in Figs. 1, 6, and 8, and in side elevation in Figs. 2, 7, and 9. In the last named figures, chime bar 17 is partly broken away. Figs. 1 and 2 show the mechanism with the movable parts in normal position. Figs. 6, 7, 8 and 9, which are fragmentary, show the movable parts in the positions assumed when chime bar 18 is being struck. Figs. 6 and 7 show the mechanism operated by a pushing action on link 12, while Figs. 8 and 9 show it operated by a pull on such link.

The chime mechanism is almost wholly constructed of a base plate 40 and of elements struck from said base plate, as will be best understood from Fig. 1.

Chime bar 17 is supported by ears 41 and 42 struck up from the base, the bar being insulated from the ears by suitable rubber washers 43. Chime bar 18 is supported by similar ears 44 and 45 also struck up from the base, this bar also being insulated from its supports by similar rubber washers 46. The first chime bar struck is 18.

Pivotally mounted at 47 on a bridge member 48, which may be spotwelded or otherwise suitably secured to the base 40, is a striker bar 49 on which, near its free end, is mounted a chime bar striker head 50, which may be made of "nylon" or other non-metallic material, such as fiber and the like. The striker head 50 may be constructed of two separate parts, one for each chime bar, or it may be formed of a single member, preferably a plastic rod having a reduced cross section intermediate its ends, and around which is rolled a holding member 50a struck

from the body of the striker bar, the member 50 fitting snugly about the striker head, the shoulders of which prevent axial movement of the striker head relative to the striker bar, due to impact between the striker head and a chime bar. Of course, the material of the striker may be varied in accord with the character of the sound desired to be produced.

On both sides of the striker bar are ears 51, which are bent downwardly. Mounted on an ear 52, which is struck up from the base, is a rubber bumper 53, situated midway between the chime bars beneath the striker bar. One or another of the ears 51 engages this button to resiliently oppose movement of the striker bar and limit the duration of contact between the striker head and a chime bar, as the striker bar swings between the chime bars, to prevent damping of the sound. The ears 51 are adjustably flexible and may be so bent as to predetermine the positions at which the rubber bumper 53 begins to oppose the movement of the striker bar. Accordingly, the angle of the ears 51 governs the force with which the striker head engages the chime bars, and therefore the intensity of the sound produced. It will be noted in Fig. 1 that the striker head is not quite in contact with chime bar 17. The striker bar is here shown in normal position, to which it is returned by the resilient buffer 53 after striking the bar 17.

The mechanism for imparting a snap action to the striker bar 49 will now be described.

Pivotally mounted at 47 above the striker bar is a bell crank 54 having three legs 55, 56, and 57. A spring 58, connected between ear 41 and leg 57, normally maintains the bell crank in the position shown in Figs. 1 and 2.

Pivotally supported on arm 55 of bell crank 54 at 59 is an arm 60 which extends to, and freely through, a slotted ear 61 which is struck upward from the striker bar. Mounted on arm 60 is a compression spring 62, the function of which is described below.

On the side of the bridge member 48 is pivoted a yoke 63. This element is shown alone in rectilinear perspective in Fig. 14. The legs 64 and 65 of the yoke are bored in alignment at 66 and 67 respectively to accommodate a suitable mounting pin 67a, which is also passed through the sides of the bridge member 48. See Figs. 2, 7, and 9. Leg 64 is provided with a dog 68, and leg 65 is provided with a dog 69 angularly displaced with reference to dog 68. Normally, dog 68 is in engagement with arm 56 of bell crank 54, and dog 69 is in engagement with arm 57 of the bell crank, as shown in Fig. 1.

The legs 64 and 65 are bent toward each other and are spaced only a small distance apart at the upper end of the yoke, as shown in Figs. 1, 6, 8 and 14. A small tongue 70 is struck from leg 64, as best seen in Fig. 14. The link 12 is provided on its rear portion with a series of holes 71, and is connected to the upper portion of yoke 63 by being passed between the legs thereof, and, depending upon the thickness of the door, and consequently upon the effective length of link required, the tongue 70 is pressed inwardly, as by pliers, so that the free end thereof passes through one of the holes 71, and serves 60 pivotally, to secure the link.

As the link is pushed, as by a push button, as shown in Figs. 7 and 13, or pulled, as by the knocker 16, the yoke is oscillated in one or the other direction. If the link is pushed, the yoke is moved as indicated in Figs. 8 and 9. Dog 69 of leg 65 of the yoke then rotates the bell crank 54 again counterclockwise by moving against arm 57. In both cases therefore, the bell crank is rotated in the same direction. As the bell crank 54 is thus rotated counterclockwise from the position of rest shown in Fig. 1, the angle between the arms 55 and 60 will increase with the simultaneous compression of spring 62, while at the same time spring 58 will be placed under tension and energy thus stored therein.

As the parts 55 and 60 pass dead center, the spring 62 will swing the striker bar 49 clockwise with a rapid, snap

action, and the striker head 50 will impinge on the chime bar 18. As soon as this happens, spring 58 will rotate the bell crank 54 clockwise and when arms 55, 60 again pass dead center, from the opposite direction, the compressed spring 62 will swing the striker bar 49 counterclockwise with a rapid, snap action to cause striking of the chime bar 17. Each operation of the link 12 in either direction, will thus produce an identical operation of the striker bar 49, and both chime bars will be struck in rapid succession and in the same sequence.

Bridge member 48 is provided with flanges 48a on either side of the center-line of the mechanism. When the yoke has been rotated a certain distance, either in response to a push or pull on the link, the oblique edges of legs 64 and 65 engage these flanges squarely and prevent further rotation of the yoke.

The base 40 of the mechanism is preferably of sheet steel, and is a shallow, rectangular pan as illustrated. A window 72, provided in the upper part of the base corresponds to window 28 of the shield which is closed by the dark mirror. Screw holes 73 are provided for screws 74 by means of which the chime mechanism and the shield may be rigidly connected together through the peephole window 11 (Fig. 2). Other holes 75 are provided for other screws 75a by means of which the base may be secured to the inner surface of the door.

It will be seen in Fig. 1 that the bridge member 48 has been struck from the cut out 76 of the base 40; the striker bar 49 from the cutout 77 and from part of the window 72 (note the dotted lines within the window); the bell crank 54 from the cutout 78; the arm 60 from the cutout 79; the yoke 63 from the cutout 80; and the link 12 from the cut out 81. The advantages to be gained from forming most of the chime mechanism from an original single sheet of metal will be apparent. Of course, the chime bars, required to be vibratile and of specially hardened metal, must be made separately.

The housing 19 is fitted over the mechanism and its base, flush with the door, and may be secured to the base in suitable manner. One of the screw holes 82 for this purpose is seen in Figs. 2, 7, and 9.

Fig. 13 illustrates, somewhat diagrammatically, another form of the invention. The essential difference between this form and that first described is in the chime mechanism housing and the wicket structure. In this figure, part of the door 10 is seen edgewise, and there is also illustrated the shield 13, a push button 83 (which, of course, may be identical with that shown in Fig. 7), the chime mechanism (indicated in dotted lines), a modified housing 84, and a modified wicket structure generally designated 85.

The chime mechanism housing 84 differs from the first described housing 19 in that it is constructed to cover only the actual chime-producing mechanism, and not also the top portion of the base 40, and consequently includes no wicket, the latter structure being independently mounted on the base.

The wicket structure 85 of the combination illustrated in Fig. 13 is shown in detail in Figs. 10, 11, and 12. The window 72 of the upper part of the base, which is in registry with the peephole window, the dark mirror, and the window 28 of the shield, is covered by a flanged dome 86, the flange 87 of which is provided with screw holes 88 for screws, not shown, for securing the dome to the upper part of base 40. A peephole 89 is provided in the dome and is normally covered by a gate or shutter 90 pivotally mounted on the inside of the dome.

Owing to the shape of the dome, the shutter 90 is in the form of a segment of a hollow sphere. A rivet 91 passed through one end of the shutter and through the wall of the dome near its flange 87, is rigidly secured on the outside of the dome to a lever 92, adapted to be depressed by the finger of the occupant of a dwelling inside the door, to move the shutter and expose the peephole. On another and oppositely disposed rivet 93, passed

through the opposite end of the shutter and through the wall of the dome near its flange, is mounted a spring 94, which normally holds the shutter in closed position, and returns it thereto when pressure of the finger on the lever 92 is removed.

The operation of the apparatus in any of its several forms described above will be apparent from the foregoing, and it will be apparent that by the present invention there is provided a chime mechanism which may be actuated to produce a like sound pattern in response to either a pushing or a pulling action on the part of the caller on the outside of the door. Either a push button or a pull knocker or the like, may be employed to operate the link 12, and no change whatsoever in the internal chime-producing mechanism, or any change in the arrangement of parts, will be required in employing the mechanism for push or pull operation.

Where a knocker, such as 16, is provided, in place of a push button, the chime mechanism may be operated either by a push or a pull on the link 12 by the knocker. It will also be apparent that the front end of the link 12 can be attached to a pull knob or the like.

Fig. 15 shows my preferred mechanism for quickly withdrawing the striker bar from contact with each of the chime bars 17 and 18, after the chime bars have been struck, in order to prevent damping of the sound.

As shown, the mechanism comprises a spring 95 connected at one end of the striker bar and at the other end to a bolt or screw 97, which passes loosely through a standard or bracket 96 which may be struck from the body of the base plate. The threaded stem of the screw is threaded into the spring and also passes through a threaded nut 98 which bears against the bracket 96. I have found that the threading of the screw into the spring provides a reliable interlock there between and upon adjustment of the screw 97, the spring 95 can be lengthened or shortened and thereby its tension varied, in order to regulate the depth of tone in the sound emitted by chime bars 17, 18. If desired, the spring can be secured to the screw in more positive fashion, as by soldering, or by perforating the screw and passing an end of the spring through the opening, in the same manner as with the striker bar 49. By the use of the spring 95, the use of the bumper 53 and tongues 51, or of stop devices, is eliminated.

Figs. 16 and 17 show a modification of the structure of Fig. 15 for controlling the tone emitted by the chime bars, while at the same time eliminating the necessity for bumpers, stops, or the like for limiting the throw of the striker bar 49. In the form of the invention, shown in Figs. 16 and 17, the bracket or post 100 which may be struck and bent upwardly from the base plate 99, is provided with a threaded aperture 101 through which passes a threaded rod 102. The rod is provided with a fixed collar 103 and at the outer end thereof there is provided a knob 104. The near end of the knob is provided with a plane surface which forms a shoulder against the unthreaded portion 106 of the rod 102 extending between the knob and the collar 103. The adjacent wall 107 of the casing, which fits over the base plate 99, is provided with a keyhole slot 109 through which the knob 104 is adapted to be passed when the casing is assembled on the base plate, the rod section 106 entering the reduced end of the keyhole slot as the casing is lowered onto the base plate.

The free end of the threaded portion of the rod 102 is received within the adjacent end of a spring 95, whose other end is secured to the striker bar, as shown. The spring receives the threaded end portion 102 in the manner of a nut, and as the rod is rotated in one or the other direction, it either enters further into the spring or partly withdraws therefrom. As a result, the effective length of the spring 95 is varied; when it is lengthened, by withdrawal of the rod 102, the tension in the spring 95 is reduced, the resistance to the oscillation of

the striker bar is likewise reduced and a stronger tone is caused to be emitted by the striker bars; while entry of the rod 102 for a greater distance into the spring 95, causes reduction in the effective length of the spring, thereby increasing the tension therein and the resistance to the movement of the striker bar, so that the latter strikes the chime bars with a weaker blow and a softer tone is produced.

In accordance with a further feature of the invention, the end wall of the casing is caused to act as a stop to limit the movement of rod 102 in both directions. When the casing is in position on the base plate 99, the unthreaded portion 106 of the rod will pass through the reduced end of the keyhole slot 109, and the end wall 107 will be disposed between the inner end of the knob 104 and the collar 103. As will be readily understood from Fig. 16, the end wall 107 will be engaged by the inner end 105 of the knob or by the collar 103 to limit the movement of the rod 102 in one or the other direction, respectively. Thereby the tone produced by the striker bars can be easily regulated at will from outside the casing. It will be evident that the distance between the knob end 105 and the collar 103 is so determined that the threaded end of the rod at no time becomes disengaged from the spring. To ensure further against such an occurrence, this spring can extend to close proximity to the bracket or post 100.

The casing 103 shown in Fig. 16 is preferably provided at its upper end with a wicket device shown in Figs. 18 to 29. The front wall 115 of the casing is provided with a peephole 116 bounded by the inwardly bent flanges 118. The peephole is controlled by a gravity shutter 117 which normally is positioned in front of the opening 116 and is controlled by a finger piece 119 having two extensions 119a and 119b which serve as stops for limiting the swinging movement of the shutter, as shown in Fig. 19. The shutter is pivoted on a pin or rivet 120 which passes through the front wall 115 and is struck down thereover. The pin or rivet is provided with a central portion 120a on which the shutter 117 is fulcrumed and at its inner end has an enlarged head 120b against which the adjacent face of the shutter bears. The shutter is provided with a guide finger 121 bent from the body of the shutter and bearing against the near face of the wall 115 to ensure proper positioning of the portion 117b of the shutter with reference to the flanges 118 defining the peephole. As will be seen from Figs. 19 and 20, the portion 117 of the shutter is bent into a different plane from the portion 117a which is pivoted on the pin 120.

It will be evident from the foregoing that upon pressure of a finger against the finger piece 119, the shutter will be lifted to expose the peephole, the part 119b limiting the swinging movement of the shutter. Upon release of the finger piece 119, the shutter will drop by gravity into closing position, being controlled in such movement by the portion 119a of the finger piece.

I claim:

1. A door chime device comprising sound producing means, mechanism for striking said sound producing means for causing the emission of sound, a manually operable member, and a connection between the manually operable member and the striking mechanism for causing the emission of sound from the sound producing means when said manually operable member is moved in either of two opposite directions and while all of the operating parts of the device remain connected in the same manner, said operating mechanism including a rocking lever and means for engaging the lever selectively from opposite directions at oppositely spaced points with respect to its fulcrum to cause rotation of the lever in the same direction when engaged upon the one or the opposite side thereof.

2. A door chime device comprising a pair of spaced chime bars, a striker bar pivotally mounted between

5 said chime bars, and means for oscillating the striker bar on its pivot to effect sounding of the chime bars, and including a rocking lever having two arms extending in opposite directions, an operating member engageable with said arms at opposite sides of the fulcrum of the lever and at opposite sides of said arms, whereby the rocking lever is rotated in the same direction whether engaged at one arm or the other, and manually operable means connected to said operating member.

3. A device as defined in claim 2, wherein the operating member comprises a yoke having spaced arms provided with longitudinally spaced projections straddling the fulcrum of the rocking lever and engageable with the opposite edges of the arms as the yoke is moved in one or the other direction.

4. A device as defined in claim 2, wherein the striker bar and the rocking lever are coaxially pivoted, and means for effecting oscillation of the striker bar by a snap action.

5. A device as defined in claim 2, wherein the striker bar and rocking lever are coaxially pivoted, said rocking lever including a third arm, an arm pivoted to said third arm and forming a reversible toggle therewith, and an overthrow spring associated with the toggle and operating to swing the striker bar by a snap action when the toggle passes dead center.

6. A device as defined in claim 5, including a return spring of greater strength than the aforementioned spring and adapted to return the striker bar to its original position.

30 7. A device as defined in claim 2, including means for pivotally supporting the yoke member, a base plate associated with the yoke member, said yoke having a portion concentric with its pivot and adapted to roll on the base plate as the yoke member is oscillated, and also a flat portion connecting with the concentric portion adapted to be stopped against the base plate as the yoke reaches one of its limits of movement, whereby said yoke and base plate are in continuous contact during the oscillation of the yoke member and mechanical noises are eliminated when the yoke member reaches a limit of its movement.

8. A device as defined in claim 2, wherein the manually operable means including a link provided with a series of apertures for the accommodation of doors of different thicknesses, and wherein the yoke member has a tongue struck from the body thereof and adapted to be pressed into one of the apertures to secure the yoke to the link.

9. In a door chime device, the combination with a 59 pair of chime bars, of a striker bar pivotally disposed between the chime bars, means for swinging the striker bar in opposite directions with a snap action, and a striker head of rod-shaped form composed of plastic material and secured to the striker bar and adapted directly to engage the chime bars.

10. A device as defined in claim 9, wherein the striker head is of reduced intermediate cross-section, and a tongue struck up from the body of the striker bar and embracing the striker head at the intermediate portion, 60 said tongue engaging the shoulders defining the intermediate portion and thereby holding the striker head against longitudinal displacement.

11. In a door chime device, the combination with a pair of chime bars, of a striker bar pivotally disposed between the chime bars, means for swinging the striker bar in opposite directions with a snap action, a striker head composed of plastic material secured to the striker bar and adapted directly to engage the chime bars, a buffer member of resilient material associated with the striker bar, and ears extending from the striker bar and arranged to engage the buffer in succession as the striker bar is oscillated, said ears being adjustable.

12. In a door chime device, the combination with a pair of chime bars, of a striker bar pivotally disposed between the chime bars, means for swinging the striker

bar in opposite directions with a snap action, and means for quickly withdrawing the striker bar from contact with the chime bar, to prevent damping of the sound, and comprising a spring and a fixed element anchoring one end of the spring, the other end of the spring being connected to the striker bar.

13. In a door chime device, the combination with a pair of chime bars, of a striker bar pivotally disposed between the chime bars, means for swinging the striker bar in opposite directions with a snap action, and means for quickly withdrawing the striker bar from contact with the chime bar, to prevent damping of the sound, and comprising a spring, a bracket, a threaded bolt mounted on the bracket and connected to one end of the spring, the other end of the spring being connected to the striker bar, whereby adjustment of the bolt effects variation in the tension of the spring.

14. A device as defined in claim 13, wherein the bolt passes loosely through an aperture in the bracket and is provided with a nut bearing against the bracket.

15. In a door chime device, the combination with a pair of chime bars, of a striker bar pivotally disposed between the chime bars, means for swinging the striker bar in opposite directions with a snap action, and means for quickly withdrawing the striker bar from contact with the chime bar, to prevent damping of the sound, comprising a coil spring connected at one end to the striker bar, a bracket having a threaded opening therein, a threaded rod threadedly engaged with the said opening and threaded into the other end of the said coil spring, said spring resisting movement of the striker bar in opposite directions, the adjustment of said threaded rod operating to vary the effective length of the spring between

the rod and the striker bar and thereby regulating the tone of the sound emitted by the chime bars.

16. A device as defined in claim 15, wherein the rod is provided with spaced stop elements thereon, said device having a casing adapted in its assembled condition to interpose an end wall between said stop elements to act as an abutment limiting the adjustment of the rod in opposite directions.

17. A door chime device comprising sound-producing means, mechanism for striking said sound-producing means for causing the emission of sound and comprising a single striker bar having a unitary striker head thereon, means for supporting said striker bar for movement in opposite directions, means connected to said striker bar for effecting initial movement of the same in one direction and against the sound-producing means, a manually operable member movable in opposite directions, and a connection between the manually operable member and said last-mentioned means for moving the striker bar in said one direction when said manually operable member is moved in either of its directions of movement and while all of the operating parts of the device remain connected in the same manner.
